UNITED STATES PATENT OFFICE.

HENRY H. TALBOT, OF ST. JOSEPH, MISSOURI.

FIREARM.

No. 882,594.

Specification of Letters Patent. Patented March 24, 1908.

Application filed October 30, 1906. Serial No. 341,298.

To all whom it may concern:

Be it known that I, HENRY H. TALBOT, a citizen of the United States, residing at St. Joseph, in the county of Buchanan and 5 State of Missouri, have invented certain new and useful Improvements in Firearms; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 The object sought by me in this invention is to provide a firearm of symmetrical design, simple construction, absolute safety from accidental or unintentional discharge, which may be fired instantly without any further 20 manipulation than grasping the handle and pulling the trigger and which will permit of construction in large as well as small calibers without loss of symmetry or practicability.

My object is attained by means of: first: 25 a shortened breech-block with its accompanying firing-pin and spring, which is of only sufficient length to entirely cover the magazine and extend back over the magazine guide lugs. Second: a complete clearance 30 of the frame to provide an unobstructed path for the hammer. Third: a hammer of such novel construction of its shank and head as will shorten its radius and place it in a more forward position with 35 in the frame reducing the over-all projection in the rear of the arm above the curvature of the handle to a minimum, thus permitting a jacket to be thrown over it. It is notched in such a manner as will permit of 40 positive retention in a cocked position, when desired, by a safety clutch. Fourth: an automatic safety of such construction that it will clutch and restrain the hammer when it is cocked at all times until pressure is 45 brought to bear upon it by the hand grasping the handle, when it is automatically retracted, freeing the hammer. Fifth: a trigger lock which, when the action is closed, permits a free movement of the trigger and 50 allows it to actuate the sear; but which, the instant the action opens, obtains powerful and mechanical possession of the trigger, regardless of any pressure which is exerted by the finger, and returns it to its forward position, thereby locking it from contact with the sear until the action is again closed and

ready to be operated. I accomplish my object by the mechanism illustrated in the accompanying drawings, in which,—

Figure 1 is a left hand, longitudinal section of the fire arm, the gun broken away, showing all the working parts of the arm except the extractor and ejector; Fig. 2 is a detail section of the trigger lock; Fig. 3 is a detail elevation of the trigger lock, shown 60 from the inside of the arm, and the recess in the carriage; Fig. 4 is a left hand longitudinal elevation of the fire arm, the gun broken away and the carriage removed, showing the ejector in place, the ejector extension shown in dotted lines; Fig. 5 is a perspective detail of the right hand side of the trigger, showing the lock notch and the bearing roll; Fig. 6 is a rear elevation of the 65 firearm; Fig. 7 is a sectional plan of the rear portion of the firearm; Fig. 8 is a detail perspective of the hammer, head and shank; Fig. 9 is a detail perspective of the trigger lock; Fig. 10 is a perspective detail of the automatic safety head, and Fig. 11 is a perspective detail of the head of the grip-bar, broken away; Fig. 12 is a detail perspective of the ejector; Fig. 13 is a detail perspective of the ejector extension and Fig. 14 is a vertical cross section of the frame, on line X—X 70 in Fig. 7, showing the ejector in place.

Similar letters refer to similar parts in the several views.

A is the frame, the walls of which are so constructed, that in the immediate rear of 90 the channel provided for the magazine there is absolutely no obstruction except a slight thickening of the walls to provide guide lugs, as shown by a^5 , Fig. 7, for the magazine, leaving an open path for the hammer to approach 95 within close proximity to the magazine channel; a is a shoulder, provided in the frame for the purpose of intercepting the point of the curved extension of the safety head d^3 , thereby arresting the outward swing of the 100 safety head.

a^1 is a slot provided in the frame for the reception of the trigger lock H; a^2 is a slot provided through the frame in the rear of the handle for the admission of the automatic 105 safety grip-bar; a^3 represents that part of the frame which provides a hood for the upper end of the safety grip-bar against which its shoulder butts in its outermost position and which provides a bearing floor 110 for the spade at the top of the safety grip-bar; a^4 is the perforation in the left wall of

the frame for the ejector retaining screw; *a⁵* is that part of the frame in the immediate rear of the magazine channel where the walls of frame thicken, forming a right and left shoulder or guide lug for the magazine; *a⁶* is the beveled recess in the left wall of the frame provided for the purpose of receiving the extension *j*, Fig. 8, of the ejector.

a⁷ is the casting in the frame which provides a seat for the rear link lug of the reciprocating barrel when it is in its rearmost position and which is slotted for the introduction of the trigger lock.

B is the carriage which is provided with an extension drawn to a closed end back of the breech block which serves as a jacket for the hammer; *b* is the breech block which is of suitable length to cover the magazine and extend over the guide lugs; *b¹* is the firing pin which is of such length as to conform with the breech block; *b²* is the firing-pin spring which is of proper length to accommodate the firing-pin; *b³* is the recess provided in the right rail of the carriage for the reception of the head of the bar of the trigger lock. This recess is such that its forward wall is an incline which in the rearward movement of the carriage wipes upon the head of the trigger lock bar, gradually depressing it until the full metal of the carriage rail contacts, holding it fully depressed until the carriage returns, when the recess being brought in proper position it permits it to rise until it is fully seated therein.

C is the hammer which is so constructed that its head may advance and form contact with the shortened breech block firing-pin; *c* is a notch provided in the top of the hammer head for engagement with clutch pawl. *d*, of the safety head; *c¹* is an upward and forward bending shank which bears the entire head forward of the vertical line of the pivotal center of the tumbler, thus permitting the striking face to advance through the unobstructed path to contact with the shortened firing-pin and breech block effecting an angle from the lower edge of the firing face to the forward rim of the tumbler, allowing the tumbler to assume a more retired position in the frame which will conform to the slant of the magazine, deviating sufficient to permit the sear to operate between them.

D is the automatic safety head, the dotted lines showing its different positions. Its movements are limited in both directions; its outward swing is arrested by the point at the lower end of the curved extension of the safety head striking a shoulder provided in part of the frame. Its inward swing is arrested by the jog or shoulder on the grip-bar, *E*, striking the reverse side of the same part of the frame. The safety head and grip-bar interlock. The full lines of the head shown in Fig. 1 represent the head when clutching the hammer. Looking at the rear end of the

arm when the safety head is in this position, it presents a smooth surface, lining with the walls of the frame and end of the carriage, perfectly. The inner dotted lines show the head when the hammer is down and there is no pressure exerted on the grip-bar. In this position the head recedes slightly into the frame, such recession being limited by the shoulder of the grip-bar striking the frame, thus offering an indication as to the position of the hammer. The outer dotted lines show the position of the head when pressure is being exerted on the grip-bar; in this position the head projects from the rear walls of the frame; *d* is the clutch pawl on the safety head for the purpose of engaging restraining notch, *c*, in the hammer head. When the safety head is in its outer position, as shown by dotted lines, this clutch pawl is withdrawn from the arc of the hammer; *d¹* is a perforation in the safety head for the purpose of receiving bearing pin *d⁴*; *d²* is a rocker cam to engage with the grip-bar *E* by means of a slot *e¹*, Fig. 11, in its head for the purpose of transmitting motion from the bar to the head; *d³* is a downward curved extension on the head terminating in a point placed there for the purpose of forming a closed joint with the frame, receiving motion for the head from the end of the grip-bar when the hammer is down and restricting the outward motion of the head by its point coming in contact with the shoulder, *a*, provided in the frame; *d⁴* is a bearing pin for the safety head which is passed through properly placed perforations in both walls of the frame and through the perforations, *d¹*, in the safety head.

E is the automatic grip-bar. It emerges from the center and rear of the handle at such a height that the ball of the thumb will engage it for its entire length, and reenters the frame above the curvature of the handle disappearing under a hood, *a³*, left for that purpose: thus it is protected from accidental discharge; *e* is a perforation in the lower end of the grip-bar for the reception of a bearing pin passed through the wall of the frame; *e¹* is a slot provided in the top of the grip-bar for the reception of the rocking cam, *d²*, of the safety head; *e²* is the top part of the grip-bar where it broadens out above the shoulder and is seated on the floor of the hood in the frame.

F is the automatic safety spring which is attached to the grip-bar, and *f* is a bearing pin for the automatic safety spring.

H is the trigger lock which, as shown, is actuated by the carriage rail, but it will be seen and understood that if preferred, the bar of the lock may be so constructed as to project through the center of the seat casting and operated by a direct tread of the rear link lug of the reciprocating barrel. *h* is that portion of the trigger lock which pro-

jects into the right hand frame channel, as shown in Fig. 3; h^1 is a right angle triangular shaped shoulder of the trigger lock, Fig. 3; this shoulder is of such shape and construction and so placed in the frame that when it makes its thrust it takes up the entire movement of the trigger with its wedge; h^2 is the actuating spring of the trigger lock, shown in Fig. 2, compressed, and in Fig. 3, expanded; h^3 is a niche in the bar of the trigger lock for the restriction of the movement of same; h^4 is a retaining screw which passes through the right hand wall of the arm and is countersunk into the wall.

15 I is the trigger; i is a beveled notch in the top and right hand side of the trigger to receive shoulder h^1 ; i^1 represents extensions or lugs at the lower end of the trigger a slot being provided between them for the purpose of receiving trigger guide and bearing roll i^2 , said extensions being perforated for the reception of bearing roll pin i^3 . The small bearing roll in the lower end of the trigger tracks on the floor of the trigger slot 20 and supports the trigger, preventing any vertical movement of the trigger when pressure is exerted from above by the trigger lock, thus making the trigger movement an absolutely straight pull.

25 30 J is the ejector which operates in a known manner, is of known construction, with the exception of an extension thereto which is provided to recess into a wall of the frame in such a manner that it lines therewith and offers no interior obstruction; j is the beveled extension provided on the ejector for admission into a beveled recess provided in the frame for the purpose of giving bearing surface for a retaining screw passed through the 35 perforation, a^4 , in the left wall of the frame. This extension is so shaped that when it is in place, it lines with the inner wall and forms the left hand magazine guide lug; j^1 is a threaded perforation in the extension j for 40 the purpose of receiving a retention screw passed through the left wall of the frame as shown by a^5 .

It will be understood from the foregoing description that the combination set forth 50 is intended for the advancement of parts to economize on space in the rear of the magazine channel above the curvature of the handle which space if practical in a small arm like a pistol, especially if constructed in large 55 calibers, is very limited and of utmost importance: it will be readily seen that if a relatively thin casting be left in the frame at the top and rear of the magazine channel and a slight change made in the hammer 60 shank the object in view would be partially attained without in any material way departing from the spirit of this invention.

It may be in the application of this invention slight deviations from the construction 65 described and shown would while obvious be

deemed by me the more desirable; therefor I would have it understood that I do not wish to restrict myself to the specific construction shown, but reserve the liberty for such departures as fairly fall within the spirit and scope of my invention.

While the foregoing description and accompanying drawings relate particularly to the mechanism of a pistol it will be understood that I do not confine myself to its use in such firearm only, but desire to cover a similar construction, either in part or combination, in any firearm.

What I claim and desire to obtain by Letters Patent is:

1. The combination in a fire arm with a carriage which contains a breech block, an extractor, an ejector, a reciprocating barrel, a recoil spring seated beneath the barrel, a magazine, a main spring, a sear, a sear trigger and magazine catch spring and a magazine catch, of a frame provided with a slot through that portion of it immediately in front of the magazine channel and above the trigger slot which intersects a hole drilled in the right wall for the reception of a trigger lock, a slot in the rear and center of the handle for the reception of a grip bar, an open rear end above the curvature of the handle for the reception of a safety head, a beveled recess in the left wall immediately in the rear and at the top of the magazine channel for the reception of the ejector extension, an open and unobstructed path for the hammer to the magazine channel, a hammer, the upward and forward bending shank of which bears the entire head forward of a line vertical with the pivotal center of the hammer tumbler, a notch in the top of the hammer, an automatic grip bar, a spring attached thereto and a bearing pin thereon, an automatic safety head adapted to interlock with said grip bar and clutch the hammer and to restrain said hammer when cocked until pressure is brought upon it by the hand grasping the fire arm handle, a trigger provided with a notch, a guide and bearing roll, a trigger lock, a shoulder thereon adapted to recover the movement of the trigger, a spring to lift the lock into the recess in the carriage rail, and a perforated beveled extension on said ejector to engage the beveled recess in the wall of said frame, substantially as shown and described.

2. The combination in a firearm with a frame having a trigger slot, the top and bottom of which are horizontal and parallel and which extend through the frame from the trigger guard to the magazine channel, a reciprocating barrel and a reciprocating breech block carriage, of a trigger having only a horizontal movement provided with a notch and a guide and bearing roll which tracks on the floor of said slot, a trigger lock, a shoulder thereon adapted to engage with

the notch and recover the horizontal, longitudinal movement of the trigger, said lock being lifted by a spring and operated by the moving parts, substantially as shown and described.

3. In a firearm the combination with the frame of an automatic safety head in line with and forming a part of the frame, a pivoted hammer, a notch in the top thereof and a clutch pawl in the safety head to engage therewith, a grip-bar provided with a slot, and a rocker cam on said safety head to engage with said slot, a downward curved extension on said head forming a closed joint 10 with the frame, and the grip-bar from the end of which said curved end receives motion for the head when the hammer is down, and the shoulder in the frame by contacting

with which the outward motion of the head is restricted, substantially as set forth and shown.

4. In a magazine pistol the combination with a frame having a recess in the inner left wall at the top and immediate rear of the magazine channel and an ejector mounted on the top of the frame, of an extension on said ejector adapted to vertically enter said recess and fill it making said frame wall continuous and offering no interior obstruction in the frame, substantially as described and shown. 25 30

In testimony whereof, I affix my signature, in presence of two witnesses.

HENRY H. TALBOT.
